CLAIM

The ornamental design for a cell phone car mount, as shown and described.

DESCRIPTION

FIG. 1 is a top perspective view of a cell phone car mount showing my new design in a closed position with a hook in a first position;

FIG. 2 is a bottom perspective view thereof;

FIG. 3 is a bottom perspective view thereof with a hook in a second position;

FIG. 4 is a bottom perspective view thereof showing my new design in an open position with a hook in a first position;
FIG. 5 is a bottom perspective view thereof with a hook in a second position;

FIG. 6 is a front elevation view of FIG. 1;

FIG. 7 is a front elevation view of FIG. 3;

FIG. 8 is a front elevation view of FIG. 4;

FIG. 9 is a front elevation view of FIG. 5;

FIG. 10 is a right side elevation view of FIG. 1;

FIG. 11 is a right side elevation view of FIG. 3;

FIG. 12 is a right side elevation view of FIG. 4;

FIG. 13 is a left side elevation view of FIG. 1 with a clamp rotated at 90 degrees;

FIG. 14 is a left side elevation view thereof of FIG. 3 with a clamp rotated at 90 degrees;

FIG. 15 is a left side elevation view of FIG. 4 with a clamp rotated at 90 degrees;

FIG. 16 is a left side elevation view of FIG. 5 with a clamp rotated at 90 degrees;

FIG. 17 is a bottom plan view of FIG. 1 with a clamp rotated at 90 degrees;

FIG. 18 is a bottom plan view of FIG. 3 with a clamp rotated at 90 degrees;

FIG. 19 is a bottom plan view of FIG. 4 with a clamp rotated at 90 degrees;

FIG. 20 is a bottom plan view of FIG. 5 with a clamp rotated at 90 degrees; and,

FIG. 21 is a top plan view thereof.
